UNITED STATES PATENT OFFICE.

JAMES P. CLARK, OF NEWARK, NEW JERSEY.

DESIGN FOR A CORNER-PIECE FOR TRUNKS AND SIMILAR ARTICLES.

No. 37,561.

Specification for Design.

Patented Sept. 19, 1905.

Application filed May 23, 1905. Serial No. 261,918. Term of patent 7 years.

To all whom it may concern:

Be it known that I, JAMES P. CLARK, a citizen of the United States, residing at Newark, in the county of Essex and State of New Jersey, have invented a new, original, and ornamental Design for Corner-Pieces for Trunks and Similar Articles, as shown in the accompanying drawing.

The drawing shows a perspective view of

a corner-piece for a trunk, showing my design.

I claim—

The ornamental design for a corner-piece for trunks and similar articles as shown.

JAMES P. CLARK.
